Primary Examiner—A. Hugo Word*Assistant Examiner*—Doris V. Coles*Attorney, Agent, or Firm*—Richard B. O'Planick; Lisa B. Reidesel[57] **CLAIM**

The ornamental design for a card for holding bait, as shown and described.

DESCRIPTION

FIG. 1 is a top right front perspective view of a card for holding bait showing our new design;

FIG. 2 is a front elevational view thereof;

FIG. 3 is a rear elevational view thereof;

FIG. 4 is a top plan view thereof;

FIG. 5 is a left side elevational view thereof; the right side being a mirror image;

FIG. 6 is a bottom plan view thereof; and,

FIG. 7 is a top right front perspective view thereof, the broken line showing of lures being for illustrative purposes only and forms no part of claimed design.

FIG. 1

FIG. 2

FIG. 3

FIG. 4

FIG. 5

FIG. 6

FIG. 7
